(57) **CLAIM**

The ornamental design for a tire, as shown and described.

DESCRIPTION

FIG. 1 is a perspective view of a tire showing my new design, it being understood that the tread pattern repeats circumferentially throughout the outer circumference and shoulder of the tire, the opposite side perspective being identical thereto;

FIG. 2 is a front elevation view thereof;

FIG. 3 is a side elevation view of the right side thereof, the left side elevation being identical thereto;

FIG. 4 is the front elevation view of FIG. 2 with a cut line 5-5; and,

FIG. 5 is a cross-sectional view taken along line 5-5 of FIG. 4.

In the drawings, the dashed lines depicting the sidewall, bead area and tire interior form no part of the claimed design.
